UNITED STATES PATENT OFFICE

167,512

VACUUM CLEANER OR SIMILAR ARTICLE

Lurelle V. A. Guild, Noroton Heights, Conn., assignor to Electrolux Corporation, Old Greenwich, Conn., a corporation of Delaware

Application April 24, 1952, Serial No. 19,463

Term of patent 14 years

(Cl. D9—2)

To all whom it may concern:

Be it known that I, Lurelle V. A. Guild, a citizen of the United States of America, residing in Noroton Heights, Connecticut, have invented a new, original, and ornamental Design for a Vacuum Cleaner or Similar Article, of which the following is a specification, reference being had to the accompanying drawings, forming part thereof.

Fig. 1 is a perspective view showing the side, top and front of a vacuum cleaner embodying my new design;

Fig. 2 is a side view of the vacuum cleaner shown in Fig. 1;

Fig. 3 is a front view of the vacuum cleaner shown in the preceding figures; and

Fig. 4 is a rear view of the vacuum cleaner shown in the preceding figures.

The side of the vacuum cleaner not shown in the drawings is the same as the side illustrated in Fig. 2.

I claim:

The ornamental design for a vacuum cleaner or similar article, as shown and described.

LURELLE V. A. GUILD.
